INCINERATOR FOR MEDICAL WASTE

Richard Goder, Chicago, Ill.

Application August 11, 1948, Serial No. 43,668

7 Claims. (Cl. 110—18)

1

The present invention relates to an incinerator for the burning of contaminated matter, such as wastes from a hospital, particularly such wastes as carry sputum or similar or like discharges by diseased patients or the like.

Among the objects of the invention is to provide a novel incinerating means having charging, combustion and exhaust chambers with a partition means therefor, preferably between the charging and exhaust chambers and having a passage for conveying distillates, gases and air, and the like from the former to the latter chambers in aiding complete and efficient combustion of the waste material and so forth.

A further object of the invention is to provide a novel grate means having a pan like portion or portions which prevent the dripping of liquid or like material, such as sputum or the like, into the ash pit or the like, and yet having sufficient air passages for the flow of air or supporter of combustion to the combustion chamber above the grate means.

Other objects, capabilities, advantages, features, and the like are comprehended by the invention as will later appear, and as are inherently possessed by the invention.

Referring briefly to the drawings:

Fig. 1 is a vertical sectional view of an embodiment of the invention;

Fig. 2 is a horizontal sectional view taken in a plane represented by line 2—2 in Fig. 1 of the drawings;

Fig. 3 is a transverse sectional view taken in a plane represented by line 3—3 in Fig. 1 of the drawings;

Fig. 4 is a top plan view of a grate part of a grate means;

Fig. 5 is a transverse sectional view taken in a plane represented by line 5—5 in Fig. 4 of the drawings;

Fig. 6 is a similar view taken in a plane represented by line 6—6 in Fig. 4 of the drawings; and,

Fig. 7 is a side view of the part shown in Fig. 4.

Referring more in detail to the drawings, the embodiment chosen to illustrate the invention is shown as comprising a housing 1 having an outer shell composed of front wall 2, rear wall 3, and side walls 4 and 5, and within the upper portion of which is provided an insulating lining or wall composed of wall portions 6, 7, 8, and 9, such walls being reinforced at the corners with reinforcing members 10, 11, 12, and 13. Around the top ends of the walls 6, 7, 8, and 9 are bars 14, 15, and 16 adapted for supporting a top 17, this top being composed of inner and outer sheets 18 and 19, and an interposed insulating sheet 20, and with the margins of the top suitably supported on the bars 14, 15 and 16. The top 17 has a charging opening 21 and an exhaust opening 22.

At the opening 21 is a closure or door frame 23 to which is pivotally connected a door 24 as by way of pivot or hinge means 25 or the like. At the exhaust opening 22 is a pipe collar or coupling 26 for connection to a smoke pipe or exhaust duct (not shown). The lower ends of the walls 6, 7, 8, and 9 are supported on suitable brackets 27, 28, and 29 suitably attached to the walls 2, 3, 4, and 5.

Transversely of the space beneath the top 17 is a cross ball 30, the ends 31 and 32 of which are held between bars 33, 33 and 34, 34 (see Fig. 2) within the walls 8 and 9. The lower ends of these bars rest on the supporting bars 29 which support the lower ends of the wall portions 8 and 9. The lower end portion of the cross wall 30 has an opening 35 at the sides of which the wall 30 has legs 36 and 37 resting on the supporting bars 29.

In the wall 30 are provided passages 38 each having a lateral inlet 39 communicating with the upper portion of a primary or charging chamber 40, and at the lower end portion an outlet 41 communicating with the opening 35 in the lower part of the cross wall 30. The walls 6, 7, 8, and 9 also have upright passages 42, 43, 44, and 45 which are open above the bars 14, 15, 16 and below the bars 27, 29 as also below the bars 28. Between the walls 30 and 7 is provided a secondary or exhaust chamber 46 communicating at its upper end with the exhaust opening 22.

Beneath the chambers 40 and 46 is a hopper 47 having inclined side walls 48 and 49 and inclined end wall 50 and converging downward to a grate means 51. The inclined walls 48, 49 and 50 have air holes 52, 53, 54, and the hopper 47 has an open forward end portion 55 located opposite an opening or burner port 56 provided in the front wall 2 of the device, and in this opening is a neck or hood or the like 57 having an inclined lower wall portion 58 extending to the grate means 51. The flame from the burner (not shown) projects into the fire space or combustion chamber 90 and the hopper 47 and above the grate means 51.

Beneath the hopper 47 and the grate means 51 is a chamber or ash pit 59 having a floor 60 forming the bottom of the device, and on this floor 60 is a collecting or ash receptacle 61 which may be withdrawn through a door opening 62 normally closed by a door 63, the latter having a suitable

handle 64 for opening the door and also having suitable air inlet control means (not shown).

In the chamber 59 is a supporting frame 65 having end walls 66 and 67 fixed to the front and rear walls 2 and 3 of the device, and side walls 68 and 69. This frame 65 has a suitable cross channel 70 into which fits and rests the lower lip portion 71 of the inclined wall 50, and likewise has longitudinal channels 72 and 73 in which fit and rest the lower lip parts 74 and 75 of the inclined walls 48 and 49 of the hopper 47. The frame 65 also has longitudinal bar members 76 and 77 for supporting the grate means 51, these bars having notches or the like 78 and 79 for the receiving and the supporting of lugs 80 and 81 of the grate pans or the like later described in connection with Figs. 3-6 of the drawings.

The grate means 51 comprises any number of grate members 82 (see Figs. 3-6) and forming part of the grate means 51 above. Each member 82 has a number of pan like depressions 83, 84, 85 and between the pans are air slots or the like 86, 87, 88, and 89 up through which air from the ash pit chamber 59 flows to support combustion in the combustion chamber 90 above the grate 51 and in the hopper 47, and down through which ash may fall to ash receptacle 61. Between the slots 86 and 87 and between the slots 88 and 89 are ribs 91 and 92. Around the pan assembly are wall portions 93, 94, 95, and 96 and within are cross walls 97, 98, 99, and 100. The lugs 80 are fixed to the wall 93 and the lugs 81 are fixed to the wall 94. A cross slot 101 also exists between a pair of members 82, 82 for passage of air and also of ash and the like as in the case of the slots 86, 87, 88, and 89.

In operation the waste material is charged into the charging chamber 40 by way of the opening 21 when the door or closure member 24 is open, the waste being guided down to the grate means 51 by the slanted walls 48, 49, 50, of the hopper 47 to occupy the space in the combustion chamber 90. The flame from the burner (not shown) is projected through the flame port 56 to the waste in the chamber 90 to burn the same. The drippings or the like from the waste will flow into the grate pans 83-84-85 to be confined therein and then evaporated to pass up to the exhaust chamber 46 and the outlet 22 with the products of combustion. The gases, vapors, distillates, and the like arising from the mass in the combustion chamber 90 into the charging chamber 40 will mix with air and pass through the passages 38 in the cross wall 30 and be discharged into the opening 35 to burn with the burning gases passing up from the chamber 90 to the exhaust chamber 46. Air passes in through the door 62-63 into the ash chamber 59 and thence up through the openings 52-53 and 54 and also up through the slots 86, 87, 88, 89, and 101 to support combustion in the chamber 90 and so forth. The liquid caught in the pans 83-84-85 will evaporate and pass off with the products of combustion to the exhaust chamber 46 and the flue port 22. The vapors, distillates, and so forth which pass up through the chamber 40 will mix with air which has also passed up thereto and flow by way of the passages 38 to the opening or space 35 to burn with the products of combustion passing from the chamber 90 to the chamber 46. But ashes may collect in the pans 83-84-85 and may be dumped into the ash receptacle by rocking the grate parts 82 about the lugs 80 and 81 as desired.

to invert them and drop the ash down into the ash receptacle 61.

While I have herein described and upon the drawings shown an illustrative form of the invention, it is to be understood that the invention also comprehends other constructions, arrangements of parts, details, features and the like without departing from the spirit of the invention.

Having thus disclosed the invention, I claim:

1. In an incinerator device of the character disclosed, which comprises a housing in which are provided a waste material receiving chamber and an exhaust chamber with a wall between said waste material receiving chamber and said exhaust chamber, a combustion chamber means located below and extending along under said waste material receiving chamber and said exhaust chamber and having an upper opening in full and free communication with said waste material receiving chamber and said exhaust chamber, a grate means at the lower portion of said combustion chamber means for supporting material to be incinerated on such grate means within said combustion chamber during incinerating, and means located in said housing for supporting said grate means in position under said combustion chamber means and said housing having a burner port means located opposite said combustion chamber means adapted to receive a burner for directing flames to the material located in said combustion chamber and on said grate means, said grate means having pan means in which liquid material may be received from the waste material located in said combustion chamber and located on said grate means for evaporation of said liquid in said pan means and exhausted by way of said exhaust chamber.

2. In an incinerating device as set forth in claim 1, and wherein said supporting means for said grate means has a pivotal means associated with said pan means for affording a tipping of said pan means for the dumping out of ashes from said pan means.

3. In an incinerating device as set forth in claim 2, and wherein said housing is provided with an ash receptacle for receiving ashes dumped from said pan means when said pan means are tipped.

4. In an incinerator device of the character disclosed, which comprises a housing in which are provided a waste material receiving chamber and an exhaust chamber with a wall between said waste material receiving chamber and said exhaust chamber, a combustion chamber means located below and extending along under said waste material receiving chamber and said exhaust chamber and having an upper opening in full and free communication with said waste material receiving chamber and said exhaust chamber, a grate means at the lower portion of said combustion chamber means for supporting material to be incinerated on such grate means within said combustion chamber during incinerating, and means located in said housing for supporting said grate means in position under said combustion chamber means and said housing having a burner port means located opposite said combustion chamber means adapted to receive a burner for directing flames to the material located in said combustion chamber and on said grate means, said grate means having pan means in which liquid material may be received from the waste material located in said combustion chamber and located on said grate means for evaporation of said liquid in said pan means and exhausted by

way of said exhaust chamber, said combustion chamber means having side wall portions extending down from said waste material receiving chamber and extending down to said grate means for forming wall portions of said combustion chamber means and for directing waste material from said waste material receiving chamber to said grate means.

5. In an incinerating device as set forth in claim 4, and wherein said downwardly extending side wall portions are provided with openings for the passage to said combustion chamber means of a support of combustion.

6. In an incinerator device of the character disclosed, which comprises a housing in which are provided a waste material receiving chamber and an exhaust chamber with a wall between said waste material receiving chamber and said exhaust chamber, a combustion chamber means located below and extending along under said waste material receiving chamber and said exhaust chamber and having an upper opening in full and free communication with said waste material receiving chamber and said exhaust chamber, a grate means at the lower portion of said combustion chamber means for supporting material to be incinerated on such grate means within said combustion chamber during incinerating, and means located in said housing for supporting said grate means in position under said combustion chamber means and said housing having a burner port means located opposite said combustion chamber means adapted to receive a burner for directing flames to the material located in said combustion chamber and on said grate means, 35 said grate means having pan means in which

liquid material may be received from the waste material located in said combustion chamber and located on said grate means for evaporation of said liquid in said pan means and exhausted by way of said exhaust chamber, and said wall between said waste material receiving chamber and said exhaust chamber being provided with a passage means having an inlet port open to the upper space of said waste material receiving chamber and having an outlet port open to said exhaust chamber.

7. In an incinerator device as set forth in claim 6, and wherein said wall has at the lower portion thereof an opening located above said combustion chamber means and between said waste material receiving chamber and said exhaust chamber and said passage means in said wall between said waste material receiving chamber and said exhaust chamber having its outlet port opening into said opening located above said combustion chamber means.

RICHARD GODER.
